MEANS FORMING RADIAL HOLES BY A VERTICALLY TRAVELING PUNCH
 Cleo Francis Carmack, 924 Thornburg St.,
 New Castle, Ind.
 Filed Apr. 20, 1962, Ser. No. 189,027
 3 Claims. (Cl. 18—42)

This invention relates to a structure for forming arcuate lengths of brake shoe lining with holes formed therethrough radially of the curvature of the lining, these holes being for the purpose of receiving rivets for attaching the lining to the brake shoe. The invention contemplates the use of brake lining material in a dough-like or plastic state so that it may be readily formed and perforated in one operation.

One of the primary problems in forming the lining is to form the rivet holes to be axially aligned with the radius of the curvature of the finished lining, doing so by a vertically reciprocable die member.

These and other objects and advantages of the invention will become apparent to those versed in the art in the following description of one particular form of the invention as illustrated in the accompanying drawing, in which

FIG. 1 is a view in fragmentary vertical section of a die structure utilized in carrying out the purpose of the invention;

FIG. 2 is a view in vertical transverse section on the line 2—2 in FIG. 1; and

FIG. 3 is a view in detail on an enlarged scale and in vertical section through one of the hole punching structures.

In FIG. 2, the structure is shown with the die members "closed" and the same thing is true of the showing in FIG. 3. The view shown in FIG. 1 shows the die members open after the brake lining member has been fully formed.

A lower die member designated by the numeral 10 has an arcuate upper face 11, the curvature of which corresponds to the curvature desired in the finished lining product. This curvature will vary in its radius of curvatures and also in the arcuate lengths depending upon the use to which the finished lining 12 is to be put. That is, whether or not it is used on the ordinary passenger car where the thickness and length of the lining will be less, or whether it is to be used on one of the heavy duty trucks where the lining will be thicker and longer with a longer radius of curvature.

The arcuate surface 11 is the floor of an arcuate cavity in the mold member 10, the depth of which will be equal to the thickness desired of the finished lining 12. This thickness is indicated by the end wall 13 as to its height.

An upper die member 14 is formed to have an under surface 15 of a curvature, the radius of which is equal to that of the lower cavity floor 11 plus the thickness of the lining 12 to be formed. The die member 14 will normally be guided for vertical reciprocation between walls 16 and 17. Also the upper die member 14 will have its lower limit of travel determined by an abutment 18 on one end and 19 on the other striking the lower die member 10.

The die member 14 has a plurality of vertically disposed bores 20 entered from its top side and extending downwardly therein. There will be one of these bores 20 for each hole to be punched through the lining. The central bore 20 will, by its vertical axis, be halfway from the ends of the member 14.

In most instances, the brake lining 12 will have sufficient width as to warrant the use of two holes side by side being formed through the lining in each instance of forming those holes clear through. For example, as indicated in FIG. 2, two bores are shown wherein each of these bores slidably receive a plunger 21. These two plungers

2

21 are secured by their upper ends to some means for pressing and lowering them, herein shown as a plate 22.

In each instance, the bore 20 is provided with a lower end counterbore 23. A punch 24 is received in the counterbore 23 and is slidably guided therein by an enlarged diameter head 25. The lower end of the counterbore 23 has a guide and stripping plate 26 through which the punch 24 may slide. This plate 26, overhangs the counterbore 23 sufficiently to form an abutment 27 against which the lower end of a compression spring 28 bears. The upper end of this compression spring 28 bears against the underside of the head 25, thereby normally urging the punch 24 to its uppermost position which will be that where the head 25 abuts the shoulder 29 at the junction of the bore 20 and the counterbore 23. Where the bores 20 are in their centrally aligned position as above indicated, the counterbore 23 will likewise in each instance be aligned axially with the bore 20.

Where holes are to be punched through the lining 12, toward its outer respective ends, the punches 24 will not be vertically reciprocated, but must be radially reciprocated. That is the punch 24 itself must reciprocate on a radial line which will form the axis of the hole. The axis therefore of the punches 24 will increase in angularity from positions nearer the center bore 20 toward the outermost positions of those bores. Likewise the lengths of plungers will have to be increased from the shortest one designated by the numeral 21 to the increasing length ranging from the plunger 21a to the plunger 21b.

The punch 24 in each instance carries a depression 30 entering its upperside. Into this depression is dropped a ball, such as a ball bearing 31. Referring first to the central bore 20, FIG. 1, and on top of that ball 31, there is dropped a spacer member 32. That is, the ball 31 and the member 32 are dropped downwardly through the bore 20. This spacer member 32 is best indicated in FIG. 3, where it constitutes a member of less diameter than that of the ball 31, and has a concave seat 33 entering it from the underside to fit the curvature of the ball 31. Then a second ball bearing 34 is dropped downwardly through the bore 20 to rest in a concave upper seat 35 in which the underside of the ball 34 rests. The plunger 21b is provided with a concave seat 36 in its lower end fitting over the topside of the ball 34. While these two balls 31 and 34 and the intervening spacer 32 may be omitted for the central bores 20, and the plunger 21 extended downwardly to come into contact with the head 25 of the punch 24, that cannot be the situation in the outermost bores 20.

For example, in the outermost bore 20 receiving the plunger 21b, the counterbore 23 is at a decided angle in respect to its axis to the axis of the bore 20. In fact the bore 20 is continued to meet and open into the counterbore 23. In this situation, the lower ball 31 will drop down (punch 24 being in its normal upper position) into this angular portion 20a of the bore to seat in the cavity 30 in the top end of the punch 24. Then the spacer 32 is dropped down onto the ball 31 followed by the ball 34, and the plunger 21b with its concave seat 36 fitting over the ball 34 as above described. The same construction is utilized in the bore 20 receiving the plunger 21a where the angularity exists, but is not as great as in the outermost location just described.

In operation, all of the plungers 21, 21a and 21b are tied together by the upper plate 22, and some mechanism (not shown) is employed particularly to lower the plate 22 to reciprocate downwardly the plungers simultaneously. With the plate 22 in the upper position as indicated in FIG. 1, and the punches 24 likewise in their uppermost positions, the material (a mixture) in its dough-like state and in the proper quantity is placed in the cavity defined by the floor 11, ends 13, and 13a, and the sides 37 and

38, and then the plate 22 is lowered so that initially the under face 15 of the upper die member 14 squeezes the lining material around over the surface 11, normally stopping the die member 14 first in its abutment on the lower die member 19, preferably utilizing springs 39 and 40 to be compressed in that lowering action and to aid in quick lifting of the die member 14 when the two die members are to be separated one from the other.

The continued downward pressure of the plate 22 on the plungers 21 causes the plungers to exert pressure on the balls 34, spacers 32 and ball 31 against the punches 24 causing them to travel outwardly or rather downwardly through the plates 27 to have their lower ends enter the lining material and form counterbores 41 therein preferably with a lower frusto-conical annular seat 42 and have the cylindrical hole punching portion 43 of the punch 24 pass on downwardly through the remaining thickness of the brake lining 12 and enter a passageway 45 provided in each instance through the lower die member 10.

Normally, it is well known, the cylindrical portion 41 is provided for wear on the brake lining 12 so as to prevent heads of rivets (not shown) normally passing through the holes 44 from rubbing on the brake drum. The frusto-conical portion is provided to accommodate the underside of the rivets which are in themselves provided with countersunk heads.

Therefore it is to be seen that with one stroke of the upper die portion 14, the brake lining 12 is squeezed into uniform thickness throughout the cavity 50 and the holes for rivets are formed. The springs 23 return the punches 24 to their normal positions as indicated in FIG. 1 from the lowered positions as shown in FIGS. 2 and 3. The returning travel of the punches 24 through the plates 26 not only guide those punches as above indicated, but keep them clean and free from accumulation of the material forming the brake lining 12.

Therefore while I have herein shown and described my invention in the one particular form, it is obvious that changes may be employed, particularly in the construction of the two die members 14 and 10, and in their mode of operation, and I therefore do not desire to be limited to that precise construction except as may be required by the following claims.

I claim:

1. In a device for forming brake shoe linings with rivet holes therethrough,
  - a first die member having a cavity with an arcuate floor therearound;
  - a second die member having an arcuate face opposing said cavity;
  - said second die member having a plurality of spaced apart bores with parallel major lengths;

each of said bores having end bore portions of minor lengths leading from said major lengths and opening through the second die arcuate face with axes thereof coinciding with lines disposed radially of said first die member floor;

a punch shiftably carried in each of said minor length bores;

a pair of balls each of approximately the diameter of and in said bores freely movable therealong;

a plunger shiftably carried in each of said bore major lengths with said balls being disposed between said punches and said plungers; and

springs normally retaining said punches in retracted positions in said bore minor lengths;

said second die member being shifted by pressure on said plungers to close over said cavity of the first die member by the arcuate face of the second die member and through said balls, overcome said springs and move said punches radially across said cavity.

2. The structure of claim 1 in which there is a spacer member between said balls with a concave cavity on opposite sides into which said balls may partially enter; said punches, each has a concave head surface into which a ball may seat; and at least one of said balls is free to traverse the junction between said major and minor bore lengths under the pressure of the plunger in one direction and a punch spring in the opposite direction.

3. The structure of claim 2 in which said minor bore lengths each has a diameter exceeding that of the major bore lengths; there is a head on each punch; one of said springs surrounds each of said punches; and there is a guide plate around each of openings of the minor bores through said second die member face, through which said punch slides, and against which the spring bears by one end, the spring bearing by the other end against said punch head.
